UNITED STATES PATENT OFFICE.

JOHN I. McCORMICK, OF CHICAGO, ILLINOIS, ASSIGNOR OF ONE-HALF TO HARRY LYTTON AND WILLIAM LYTTON, BOTH OF CHICAGO, ILLINOIS.

SLOT GUARD OR SHIELD.

1,104,370.

Specification of Letters Patent.

Patented July 21, 1914.

Application filed November 24, 1913. Serial No. 802,725.

To all whom it may concern:

Be it known that I, JOHN I. McCORMICK, a citizen of the United States, residing at Chicago, in the county of Cook and State of Illinois, have invented certain new and useful Improvements in Slot Guards or Shields, of which the following is a specification.

This invention relates to improvements in slot guards or shields, particularly adapted, though not necessarily limited in its use with automobiles.

Heretofore considerable inconvenience and discomfort have been experienced by the operators of automobiles, in warm weather, in that the heated air from the engine is forced against the feet of the operator, through the slots in the bottom of the car, and in which slots the controlling treadles operate.

20 In order to prevent the heated air from being directed against the operator's feet through these slots, and at the same time form closures for the slots, without interfering with the operation of the treadles is 25 one of the objects of the present invention.

A further object is to provide an improved device of this character, which will be simple, durable, and cheap in construction, and effective and efficient in operation, 30 and which may be readily applied.

To the attainment of these ends, and to the accomplishment of other new and useful objects as will appear, the invention consists in the features of novelty, in substantially the construction, combination and arrangement of the several parts hereinafter more fully described and claimed and shown in the accompanying drawing illustrating the invention, and in which:

40 Figure 1 is a sectional view of a portion of an automobile, having an attachment applied thereto, constructed in accordance with the principles of this invention. Fig. 2 is a top plan view of a removable portion of 45 the floor of the vehicle through which the slots pass, with the invention attached thereto. Fig. 3 is a bottom plan view of the parts shown in Fig. 2, and slightly separated. Fig. 4 is a detail sectional view 50 taken on line 4—4, Fig. 2. Fig. 5 is a view similar to Fig. 4 showing one of the treadles passing through one of the slots, and the

position the parts of the guard or shield will assume.

Referring more particularly to the drawing and in the present exemplification of this invention, the numeral 10 designates generally a portion of the car body and 11 designates the engine hood. Arranged adjacent the dashboard 12 of the car is an inclined portion of the floor or foot board and which portion or board is preferably constructed in sections 13, 14 having overlapping shoulders 15, and through which portions 13, 14 slots 16 pass and through each 65 of which slots a controlling treadle 17 passes, all of which is of the ordinary and well known construction.

A frame 18 having slots 19 therein is also provided and is of sectional construction, 70 and the sections of the frame 18 are secured to the sections 13, 14 of the floor so that the slots will register.

The guard or shield for preventing the heated air from passing through the slots 75 16, 19 may be of any desired construction and of any suitable material. In the present invention this guard or shield is constructed of flexible material 20, arranged in two sections, one edge of each section being secured 80 to the lower face of the removable floor section, and on opposite sides of the slot 16 therethrough. These sections of the flexible material 20, are of such a size that the faces of their adjacent ends will abut, and 85 will project for some distance below the face of the floor section and in alignment with the slot 16 as shown in Fig. 4. The flexible sections may be secured to the floor in any suitable manner such as by means of 90 clips 21 through which fastening devices 22 pass, and if desired additional sections 23 of flexible material, similar to the sections 20 may also be secured to the face of the removable floor section by the clips 21 and 95 fastening devices 22. These sections 23 are of a size that the adjacent edges thereof will abut, in alignment with the slot 16, but will be normally held substantially parallel with and substantially flat against the face of 100 the floor section. The controlling treadle 17, passing through the slot 16, will also pass between the sections 20 and 23 of the shield or guard and will cause the latter to be

separated or deflected as shown in Fig. 5. Thus it will be manifest that inasmuch as the shield or guard is constructed of flexible material, the treadles may be readily 5 operated, and as they are moved forward or backward in the slots, the sections of the shield or guard will yield to permit the treadles to operate and at the same time will form closures for the slots to prevent the 10 heated air from passing therethrough. Inasmuch as the sections of the shield or guard are flexible, it will also be manifest that any draft or current of heated air directed against the under faces thereof, will have a 15 tendency to force the sections together and closely about the portion of the controlling treadle passing through the slot.

In order to permit the floor sections 13, 14 to be readily removed, the shield or guard is 20 of a sectional construction as shown in Fig. 3, a portion thereof being secured to the face of the floor section 13, while the portion which is secured to the section 14, of the floor, projects beyond the edge of the floor 25 section as at 24 so that when the floor sections are assembled, the projecting portion 24 of the shield will overlap the portions of the shield which are secured to the floor section 13.

30 While in the present exemplification of this invention, the preferred form, and construction is herein shown and described, it is to be understood that various changes may be made, in the details of construction, combination and arrangement of the several parts without departing from the spirit of this invention, therefore the drawings are to be considered as being merely diagrammatic.

What is claimed new is:—

40 1. In a motor vehicle the combination of a controlling lever, a sectional foot board, the sections of said board having recesses opening through their adjacent edges and coöperating to form a slot in which the lever operates, and a sectional flexible shield, the sections of the shield connected with the 45 respective sections of the foot board and forming a closure for the slot.

50 2. In a motor vehicle, the combination of a controlling lever, a sectional foot board, the sections of said board having recesses opening through their adjacent edges and coöperating to form a slot in which the lever operates, and a sectional flexible shield, the 55 sections of the shield connected with the respective sections of the foot board and forming a closure for the slot, said shield sections being detached from the lever, successive portions of the shield being deflected by the lever as the latter is moved lengthwise of the slot.

60 3. In a motor vehicle, the combination of a controlling lever, a sectional foot board, said sections having recesses coöperating to 65 form a guide slot in which the lever operates,

and a shield forming a closure for the slot, said shield embodying sections of flexible material detached from the lever and from each other, said sections arranged on the opposite sides of the slot, extending in directions across the slot and removable with the respective sections of the foot board. 70

4. In a motor vehicle, the combination of a controlling lever, a sectional foot board, said sections being freely removable and having coöperating recesses forming a guide slot through which the lever passes, and a guard for the slot, the said guard embodying separable flexible sections secured on opposite sides of the slot to the respective board sections, detached from each other and projecting in directions across the slot, the proximate edges of the sections abutting and being normally deflected away from the slot, said abutting portions being in alinement 80 with the slot, and between which portions the lever operates. 85

5. In a motor vehicle, the combination of a controlling lever, a foot board comprising removable sections, the sections having recesses coöperating to form a guide slot through which the lever passes, a guard for the slot, said guard embodying flexible sections secured on opposite sides of the slot to the respective board sections and to project in directions across the slot, the proximate edges of the guard sections abutting and being normally deflected away from the slot, said abutting portions being in alinement with the slot, and between which portions the lever operates, and additional sections secured to the respective board sections to co-operate with the first recited guard sections and extending in directions across the slot, the lever also passing between the proximate edges of the second recited guard sections, said lever being detached from all of the sections. 90 100

6. In a motor vehicle, the combination of a sectional foot board, the sections having recesses opening through adjacent edges and coöperating to form a slot therethrough, a controlling lever operating in the slot, and a guard for the slot, said guard embodying separable flexible members supported by the element on opposite sides of the slot, independent of the lever and extending toward each other in directions across the slot, the proximate portions of the members abutting in alinement with the slot and being deflected away from the face of the slotted element, and between which deflected portions the lever operates. 110 115 120

7. The combination of an element embodying separable sections and having a slot extending through the sections and across the joint therebetween, a guard for the slot embodying separable flexible members supported by the respective sections to extend in directions across the slot and from op- 125 130

posite sides thereof, the proximate edges of the members abutting in alinement with the slot, a lever operating in the slot and passing between the flexible members and detached from the members, said guard members normally closing the slot but yielding to the movement of the lever.

In testimony whereof I have signed my

name to this specification, in the presence of two subscribing witnesses, on this 22nd day of November A. D. 1913.

JOHN I. McCORMICK.
